W. C. REYNOLDS.
SEED POTATO CUTTER.
APPLICATION FILED APR. 21, 1921.

1,391,505.

Patented Sept. 20, 1921.

UNITED STATES PATENT OFFICE.

WILLIAM C. REYNOLDS, OF REMUS, MICHIGAN.

SEED-POTATO CUTTER.

1,391,505.

Specification of Letters Patent. Patented Sept. 20, 1921.

Application filed April 21, 1921. Serial No. 463,107.

To all whom it may concern:

Be it known that I, WILLIAM C. REYNOLDS, a citizen of the United States, residing at Remus, in the county of Mecosta and State of Michigan, have invented certain new and useful Improvements in Seed-Potato Cutters, of which the following is a specification.

The object of this invention is to provide an apparatus by the use of which seed potatoes may be cut into pieces suitable for planting rapidly and with certainty. One object of the invention is to provide means whereby the potatoes will be supported in position to be properly engaged by the knife and held against slipping when the knife comes into contact therewith and a further object of the invention is to provide means whereby, as the knife is retarded, it will be cleaned of all particles tending to adhere thereto. Other objects of the invention will appear incidentally in the course of the following description.

The invention is illustrated in the accompanying drawings, in which—

Figure 1 is a perspective view of one embodiment of the invention;

Fig. 2 is a transverse section;

Fig. 3 is an enlarged detail view of the knife and the combined guard and cleaner therefor.

In carrying out my invention, I employ a supporting frame 1 which may be of any convenient or preferred construction and at one side or end of the frame I erect a standard 2 upon which the knife 3 is pivoted. Upon the frame, I support a hopper 4 which may have an open side across which the knife 3 is mounted to play and along which, at the bottom thereof, is provided a trough 5 in which the potatoes to be cut are received from the hopper. The trough is conveniently constructed by placing two boards or rails at an angle to each other so that they converge downwardly and have their lower edges slightly separated, as shown at 6, whereby the cutting edge of the knife may pass between the boards or trough members and be thereby enabled to pass entirely through the potatoes. End rails 7 are provided below the bottom 8 of the hopper and are extended beyond the open side thereof so that they furnish firm supports for the rails which constitute the trough. The post or standard 2 projects

above the hopper and may be utilized as a closure for one end of the trough, this arrangement obviously locating the knife directly in the vertical plane of the trough, as will be readily understood. While the knife may be pivoted to the standard in any desired manner, I prefer to provide a slit 9 in the standard and pivotally secure the end of the knife in said slit. The knife is of such dimensions that it will extend entirely across the open side or front of the hopper and at its free end is equipped with a convenient handle 10. A retractile spring 11 is attached at one end to the standard and at its opposite end to the blade and tends constantly to hold the blade or knife in its raised position, shown in Fig. 1. To aid in holding the knife to the proper plane for its successful operation, I provide a guide 12 which may conveniently be a strip of metal secured to the standard or post 2 near the upper end of the same and extending therefrom in an arched formation over the hopper to the end of the same remote from the standard, and the extremity 12' of this guide is preferably a hinged leaf normally extending into the trough to prevent the potatoes rolling therefrom. When the cut potatoes are manually pushed from the trough, the leaf will yield and permit their discharge, returning to normal position by gravity after the potatoes have passed.

I also provide a combined guard and cleaner for the knife consisting of a strand wire bent to provide a fork or yoke 13 fitting over the upper edge of the knife adjacent to the point at which the spring 11 is attached thereto and this yoke should grasp the sides of the blade closely but with sufficient play to yield to the impact upon the potatoes in the trough. From the lower ends of the yoke 13, the wire is carried rearwardly, as shown at 14, and then doubled upon itself and brought forwardly along the blade or knife, as shown at 15, to the handle 10, this formation being duplicated upon the two sides of the knife, as will be readily understood. Adjacent the handle 10, the ends of the wire are bent upwardly so as to lie close to the end of the handle and one extremity of the wire, as shown at 16, is wrapped or twisted around the meeting portion of the wire, after which the said meeting portion is extended along the upper edge of the knife, as shown at 17, and soldered 110

or otherwise attached to the top of the yoke 13. This combined guard and cleaner should be more or less resilient so that it will fit the knife snugly and will tend constantly to bring its upper longitudinal member 17 to bear upon the back of the knife, while the lower strands 15 will lie immediately adjacent the cutting edge of the knife.

The potatoes to be cut are placed in the 10 hopper 4 and any convenient plate or small board may be placed on edge against the guard 12 to serve as a closure for the open side of the hopper to prevent the potatoes rolling precipitously therefrom. After the 15 potatoes have been placed in the hopper, they are crowded to the back thereof and the plate removed. A few potatoes are then fed into the trough and will naturally assume positions with their longer axes disposed longitudinally of the trough. If the knife be then brought down into the hopper to the position shown in Fig. 2, it will cut through the potatoes and the strands 15 of the guard will bear upon the potatoes so as to prevent rotation thereof and hold them firmly in position to be acted upon by the knife. As the knife cuts through the potatoes, the guards will relatively move upwardly, but, when the knife is released, the spring 11 will at 25 once raise the same and the guard will resume its normal position, the knife or blade passing into the yoke end portions of the guard so that the longitudinal strands 15 will be caused to slide relatively over the sides of the knife and remove therefrom all particles of the potatoes which might adhere thereto. As the knife is brought down onto the potatoes, it will be held against the edge of the 30 guide strip 12 and this guide strip is preferably so arranged that unless the knife be bent out of the vertical plane of the slit 9 there will be constant contact between the edge of the guide and the adjacent strand 15 of the guard. The frictional engagement between the guide and the guard aids in holding the guard to its position upon the knife.

My device is obviously simple in the construction and arrangement of its parts and may be produced at a low cost. The knife

may be operated easily and rapidly and by its use a large number of potatoes may be cut in a very small period of time.

Having thus described the invention, what is claimed as new is:

1. A seed-potato cutter comprising a hopper having an open side, a trough extending along said open side to receive potatoes therefrom and having an opening through its bottom, a knife pivotally mounted at one end of the trough and adapted to extend into the opening of the bottom of the same, and means for yieldably holding the knife in a raised position. 55

2. A seed-potato cutter comprising a hopper having an open side, a trough extending along said side to receive potatoes therefrom, a post erected at one end of the trough, a knife pivoted upon said post and adapted to play in the trough, a retractile spring connected to the knife and to the standard above 60 the knife. 65

3. A seed-potato cutter comprising a hopper, a trough along one side of the hopper to receive potatoes therefrom, a knife pivotally mounted at one end of the trough and adapted to act upon the potatoes in the trough, and a guard fitted upon the knife to engage the potatoes and hold the same against rotation as they are acted upon by the knife. 75

4. A seed-potato cutter comprising a hopper, a trough arranged to receive potatoes from the hopper, a pivotally mounted knife operating in the trough, and a guard slidably but snugly engaging the sides of the knife and moving upwardly relative to the 80 knife as potatoes are engaged and downwardly relative to the knife as the knife recedes from the potatoes. 85

5. In a seed-potato cutter, the combination of a pivotally mounted knife, and a guard 90 consisting of yokes engaging over the knife at the ends thereof, and connecting strands extending between said yokes along the back of the knife and at opposite sides of the knife adjacent the cutting edge thereof. 95

In testimony whereof I affix my signature.

WILLIAM C. REYNOLDS. [L. S.]
